COLLECTION OF ARTIFICIAL YARN ON RING SPINDLES

Sydney Warren Barker, Colne, England, assignor to Lustrafil Limited, Nelson, England

Application November 24, 1948, Serial No. 61,773
In Great Britain November 27, 1947

3 Claims. (Cl. 57—75)

1

This invention relates to the collection of artificial threads on ring spindles, and in particular to a method of starting the winding on ring spindles, and to apparatus therefor.

In the continuous production of artificial threads, the thread after leaving the spinneret is subjected to various treatments and after being dried is wound on bobbins. It has been customary to use cap spinner bobbins since the start of the winding in this case is conveniently easy even with high thread speeds, which in modern processes are of the order of 60 yards per minute and may reach 200 yards per minute or more.

In the continuous production of artificial threads the thread issuing from the spinneret into the coagulating medium is led on to thread-storing, thread-advancing rollers where coagulation is completed and the thread is subjected to any desired treatments with liquids and dried. The dried thread is collected on bobbins mounted on rapidly revolving vertical spindles. These are either cap spinners or ring spinners. In both types the thread is led on to the bobbin through a guide which, by a suitable up and down traverse motion of the bobbin or of the guide directs the thread to successive portions of the bobbin. The guide in the case of cap spinning takes the form of a bell-shaped hood or cap suspended over the spindle, and either the cap or the spindle moves at an appropriate speed up and down. In ring spinning the guide is a hook or "traveller" attached to and free to move round a metal ring concentric with the axis of the spindle; in this case the ring executes the traverse motion which directs the thread to successive parts of the bobbin.

The spindle is set to revolve at a predetermined angular speed which gives to the bobbin a peripheral speed considerably greater than the rate of delivery of the thread to the collecting device. The result of the difference between the speed of the on-coming thread and the peripheral speed of the bobbin is that the thread is whirled rapidly round the bobbin in addition to being wound on the bobbin. In cap spinning the thread slips round the bottom edge of the cap, whilst in ring spinning the ring traveller is whirled round the metal ring.

This ballooning rotation of the thread imparts a twist to it, and the angular speed of the spindle is so chosen in relation to the speed of delivery of the thread as to produce the desired number of "turns" per inch of thread.

Thus, suppose thread is being delivered at 400 ft. per min. on to a bobbin of 1.27 inch diameter,

2

i. e. 4.0 inch circumference, rotated by a spindle at 4,000 R. P. M. The rate of delivery of the thread will be equal to 1200 R. P. M. of the bobbin. The ballooning thread will therefore be whirled round the bobbin at 4000 minus 1200, i. e. 2800 R. P. M. There will thus be 2800 twists imparted per minute, i. e. per 400 feet of thread, or .583 "turn" per inch.

Ring spinning has several advantages over cap spinning. The spindles are simpler; the tension on the thread is more readily controlled, and since the traverse motion is executed by the light-weight ring and not by the package there is saving in power, and large packages can be wound without trouble.

Ring spinners are therefore preferred, but with high speeds of thread delivery starting up a new bobbin presents a serious problem, since it is then impossible for the operator to deal by hand with the slack which accumulates during the time occupied in threading the guides and casting the thread on to the bobbin.

Various procedures have been proposed in the prior art for solving this problem.

Thus, in one method, the oncoming thread was led to a vacuum suction nozzle through which it was drawn into a tube. This disposed of the surplus thread and the operator was enabled to guide the thread through the ring traveller, to pull it down through the ring and to flick it on to the bobbin, at the same time severing the thread between the bobbin and the vacuum nozzle.

Alternatively the oncoming thread was taken to a draw roller having a peripheral speed equal to or somewhat less than the speed of the thread. The thread on its way to the draw roller could then be diverted to the ring traveller, pulled down through the ring, flicked on to the bobbin and severed as before.

In another procedure a separate auxiliary piece of thread was wound round the empty bobbin, the free end passed through the ring traveller and the bobbin placed on the stationary spindle. The free end of the auxiliary thread was then taken up through the lappet guide, the spindle started, the free end twisted into the on-coming thread above the lappet guide and the accumulated waste thread broken off below the joint, on-coming thread above the join being pulled on to the bobbin by the auxiliary thread.

In all these prior methods there are several operations, and the last one in each case is difficult, requiring considerable dexterity to reach any reasonable degree of efficiency.

It is an object of the present invention to provide a simple, rapid and easy method of starting up the collection of thread on a ring spinner, suitable for use with even the highest delivery speeds. Further objects will appear from the following description of the invention.

In the method of the invention use is made of a two-speed spindle drive, the lower speed giving to the bobbin a peripheral speed approaching but not exceeding the rate of delivery of the thread, whilst the higher speed is the normal speed for ring-spindles, for example, 4,000 to 6,000 R. P. M., i. e. 10 to 20 times the lower speed.

According to the invention in starting up a new bobbin the bobbin is placed on the spindle revolving at the lower speed, the on-coming thread is taken by hand, either via the lappet guide or direct, to the bobbin. The thread is then taken through the ring traveller (and through the lappet guide if that has not already been done). Finally the higher speed drive is thrown into operation and the spindle picks up normal speed. The operation of starting up occupies only a very few seconds, and there is no accumulation of waste thread during the operation, the bobbin itself providing the reservoir for the thread delivered during the threading of the guides.

A large number of devices for dual speed drives are known and are suitable for use in the method of the invention. They include means for disengaging the normal drive (or allowing slippage) and engaging an appropriately lower drive, e. g. by the use of a movable geared shaft, or of a movable intermediate gear, or of a two-speed electrical drive, or by other means such as an epicyclic chain of wheels inside the spindle pulley itself. In combination with any of these modifications of the drive there may be introduced means for lifting the normal driving tape off the spindle pulley during the time when the secondary speed gear is in operation or means for allowing the driving tape to become slack and so permitting it to slip over the spindle pulley during that time.

In order that the invention may be more readily understood, reference is made to the accompanying drawings, wherein:

Fig. 1 is a diagrammatic view illustrating the initial threading of the thread on to a bobbin,

Fig. 2 is a diagrammatic side elevation showing a bobbin spindle and one example of a means whereby the bobbin may be selectively driven at normal speed by a tape drive or at an appropriately slower speed for threading purposes by a mechanism including a slidable spiral gear,

Fig. 3 is a view similar to Fig. 2, but illustrating a modified form of the secondary speed drive, and

Fig. 4 is a part sectional view of a bobbin spindle fitted with an induction-type motor for producing two different spindle speeds.

Fig. 1 shows diagrammatically the starting-up of winding on a bobbin 5 on a ring-spindle 6 driven by pulley 7 and tape 8. The on-coming thread 1 is taken by hand and given a turn round the bobbin 5 at a convenient distance above the ring 4, the bobbin 5 meanwhile being rotated by the spindle 6 driven at such reduced rate (by such means as are more specifically shown in Figs. 2, 3 and 4) as to give to the surface of the bobbin a peripheral speed equal to or slightly less than the linear speed of delivery of the thread. The thread at this stage is wound on the bobbin 5 as fast or almost as fast as it is delivered, and little or no slack accumulates. The loop of

thread 11 is next taken by a finger 9 of the other hand and caught in the ring-traveller 3 on the ring 4, and if it does not already pass through the lappet guide 2 it is at the same time made to do so. During this stage of the operation the windings on the bobbin 5 will descend to the level of the ring 4 under the guidance of the hand threading the ring-traveller 3. Finally the spindle drive is allowed to pick up normal speed. Winding and twisting now proceeds smoothly, the thread ballooning out as shown at 10 and being directed to the appropriate successive portions of the bobbin by the relative up and down motion between ring 4 and bobbin 5.

Fig. 2 illustrates one example of a means for selectively driving the spindle at two different speeds. The spindle 12 is an axial extension of a vertical shaft 13 which is integrally formed with a pulley section 14. A tape 15 extends around the pulley 14 and also around another pulley (not shown), the latter being driven by any suitable power unit to rotate the pulley 14 and thus the spindle 12 at a normal running speed, e. g. 5000 R. P. M. Pivoted carried by the shaft 13 below the pulley 14 is a spring-urged arm 16 carrying a jockey pulley 17, which, in known manner operates to tension the tape 15. Fixed to the shaft 13 below the arm 16 is a spiral gear 18. Slidable parallel to the shaft 13 is a second shaft 19 carrying at its upper end an intermediate spiral gear 20 adapted when the slidable shaft 19 is moved to its uppermost position as hereinafter described to mesh with the first-mentioned spiral gear 18 and also with the third spiral gear 21 mounted at the end of a horizontal drive 22 the latter being independently driven by means not shown.

When initially threading or re-threading a bobbin carried by the spindle 12, a lever or other shifting means (not shown) is actuated to displace the slidable shaft 19 upwardly from the full-line to the dotted-line position to mesh the intermediate spiral gear 20 with the gears 18 and 21 and at the same time to swing the jockey pulley 17 from its full-line position tensioning the tape 15 to its dotted-line position in which the tape 15 is disengaged from the spindle pulley 14. Thus the normal drive through the tape 15 is rendered inoperative and the spindle is driven at a slower speed, e. g. 450 R. P. M. through the shaft 22 and the gears 21, 20 and 18.

Fig. 3 illustrates a modification of the arrangement shown in Fig. 2, and corresponding parts in both figures are indicated by the same reference numerals. Referring to Fig. 3, it will be seen that the spindle 12 and the spindle shaft 13 with its pulley 14 are of the same construction as in Fig. 2, but that the spiral gear 18 is replaced by a spur gear 23. The secondary drive shaft 22 again carries a spiral gear 21, but the intermediate gear 20 is fixed intermediate the ends of a vertical shaft 24, said shaft ends being journaled in bearings to a bracket 25 mounted to pivot about the secondary drive shaft 22. The upper end of the vertical shaft 24 carries a spur gear 26 which may be brought into mesh with the first-mentioned spur gear 23. The operation of this arrangement is similar to that described with reference to Fig. 2. For threading or re-threading, a lever (not shown) is actuated which simultaneously pivots the second-mentioned spur gear 26 from its dotted-line position into its full-line position in mesh with the gear 23, and swings the jockey pulley 17 to render the tape drive inoperative as above described. The spindle is

thus driven at an appropriately slower speed, e. g. 450 R. P. M. until, gears 26, 23 are disengaged and the tape driver is again rendered operative to drive the spindle at its normal running speed, of, for example 5000 R. P. M.

Thus, with both of the examples above described, there is, in effect provided a two-speed gear by which the spindle 12 may be selectively driven at normal running speed or at an appropriately slower speed for threading purposes.

Fig. 4 illustrates diagrammatically an arrangement whereby the two different speeds are produced electrically. In this arrangement, the bobbin spindle 12 is equipped with a small induction-type electric motor 32 supported on a suitable bearing 33. The base 34 of the bobbin 35 and the spindle 12 above the motor 32 are preferably fitted with insulating block 36. The motor 37 is secured to the spindle 12 and electric current is supplied to the motor windings 38 through the lead 39 and the double-throw switch 40. Two sources of electric current are provided, for example, one at 8.5 cycles per second, giving a spindle speed of 490 R. P. M., and the other at 110 cycles per second, giving a spindle speed of 6500 R. P. M., so that simply by moving the switch 40, the spindle 12 may be rotated at its normal running speed or at slow speed for threading purposes.

Although three arrangements for selectively driving a spindle at two different speeds are illustrated in the accompanying drawings and have been above described, it is obvious that there are many other ways in which this result may be achieved. For example, there may be provided, on the spindle shaft, a pair of coaxial tape pulleys each open at its inner end so that together they form a casing for a two-speed epicyclic gearing so arranged that when the drive is round one of the pulleys, the spindle is rotated at a relatively slow speed, e. g. 490 R. P. M. for threading purposes, and when it is round the other of the said pulleys, the spindle is rotated at its normal running speed. Any suitable and well-known belt-shifting mechanism would be provided for selectively displacing the tape to the desired pulley.

I claim:

1. A method of commencing the winding of rapidly delivered thread on ring-spindle bobbins

which comprises (a) reducing the drive of the ring-spindle to such a rate that the peripheral speed at the surface of the bobbin approaches but does not exceed the linear rate of delivery of the thread, (b) leading the on-coming thread to the empty bobbin on the ring spindle and giving it a turn thereon above the level of the ring so that the thread is wound on the bobbin revolving at the reduced speed, (c) passing the on-coming thread through the ring-traveller, and finally (d) restoring the ring-spindle drive to normal speed.

2. A method of commencing the winding of rapidly delivered thread on ring-spindle bobbins which comprises (a) leading the on-coming thread through a lappet guide to the empty ring-spindle bobbin and giving it a turn thereon above the level of the ring, the ring-spindle at this stage being driven at such reduced rate that the peripheral speed at the surface of the bobbin approaches but does not exceed the linear rate of delivery of the thread, (b) allowing the thread to be wound on the bobbin whilst guiding the thread by hand so that successive turns of thread approach the level of the ring, (c) immediately that level is reached passing the thread through the ring-traveller, and finally (d) restoring the ring-spindle drive to normal speed.

3. A method of starting the winding of rapidly delivered thread on ring-spindle bobbins which comprises, driving the ring-spindle at such a rate that the peripheral speed at the surface of the bobbin approaches but does not exceed the linear rate of delivery of the thread, leading the on-coming thread to the empty ring-spindle bobbin and giving it a turn thereon above the level of the ring so that the thread is wound on the bobbin, passing the on-coming thread through the ring-traveller, and finally increasing the rate of ring-spindle drive to normal speed.
